(57) **CLAIM**

The ornamental design for a surgical strike plate handle for implant removal, as shown and described.

DESCRIPTION

FIG. 1 is a front side view of a strike plate handle for implant removal showing our new design;

FIG. 2 is a back side view thereof;

FIG. 3 is a left, side view thereof;

FIG. 4 is a right, side view thereof;

FIG. 5 is a top plan view thereof; and,

FIG. 6 is a bottom plan view thereof.

The broken lines shown in the surgical strike plate handle for implant removal are for portions that form no part of the claimed design.

1 Claim, 3 Drawing Sheets
